UNITED STATES PATENT OFFICE.

FRANK G. DUNORTH, OF CENTERVILLE, MICHIGAN, ASSIGNOR OF ONE-HALF TO
RUSSELL D. WAGNER, OF CENTERVILLE, MICHIGAN.

TOOL FOR REMOVING HEADLIGHT LENSES.

Application filed August 5, 1922. Serial No. 579,855.

To all whom it may concern:

Be it known that I, FRANK G. DUNORTH, a citizen of the United States, residing at Centerville, county of St. Joseph, State of Michigan, have invented certain new and useful Improvements in Tools for Removing Headlight Lenses, of which the following is a specification.

This invention relates to an improved tool for removing headlight lenses.

The object of the invention is to provide an effective and simple tool that will grasp the ringer cap without danger of injuring the same and permit the operator to have an effective double hand hold for manipulating the same to release it from its catches or to unscrew the same, depending on the kind and style of fastenings that may be employed for the purpose.

Objects pertaining to details and economies of construction and operation will definitely appear from the detailed description to follow.

I accomplish the objects of the invention by the devices and means described in the following specification. The invention is clearly defined and pointed out in the claims.

A structure which is a preferred embodiment of my invention is clearly illustrated in the accompanying drawing, forming a part of this application, in which:

Fig. I is a detail perspective view of a headlight with my improved lens removing tool in process of being applied thereto.

Fig. II is a front elevation view of the tool when not in use.

Fig. III is an enlarged detail sectional view on a line corresponding to line 3-3 of Figs. I and II, showing the relation of the tool to the lens rim or cap and the relation of the projecting cushion within the same, looking in the direction of the little arrows at the ends of the section lines.

Fig. IV is a detail front view similar to Fig. II of a slightly modified construction.

In the drawing similar numerals of reference refer to similar parts throughout the several views.

The parts of the drawing will be considered by their numbers. 1 is an automobile headlight supported on the usual suitable fork 2. 3 is the lens retained by a

lens cap or ring 4 in position in front of the reflector 5 against the usual gasket 51, these parts being conventionally illustrated. The lens cap or ring 4 is secured to the body 1 of the headlight in any of the usual well-known ways. Some are secured by a screw thread, others by a bayonet joint, others by a simple catch means, all of them requiring manipulation of the ring or cap, which is often and usually very difficult for the hands of the operator. This manipulation is for the freeing of some sort of locking catch or means involving movement in addition to the mere turning movement.

I have not illustrated the different methods of securing this ring or cap in place or the different forms thereof because they are greatly varied in practice and my invention does not pertain to the fastenings but to an effective means of grasping the ring or cap so that it may be effectively handled by the hands of an operator.

The tool is similar to an enlarged can cover wrench but is differently constructed and provided with two opposed handles whereby effective manipulation of the lens cap or ring can be accomplished. These parts consist of two semi-circular parts, 6 and 7, L-shaped in cross section to form cushion seats having handle parts 61 and 71, respectively, from one adjacent side secured together by a suitable hinge 8. Separate handles 62 on the segment 6 secured by the rivets 63 and 72 on the segments 7 secured by rivet 73 are disposed in proximity to each other on the opposite side whereby they may be grasped by the hand of an operator and clamped tightly upon the lens cap or ring.

Segmental cushions 9 are disposed within the L-shaped cushion seats,—see Fig. III, being retained in position by screw bolts 10 with nuts 11 at the inner end suitably recessed in the cushion.

From what I have described it will be seen that the tool can be opened up and placed in position on a headlight ring or cap and the operator by grasping the handles 62 and 72 will clamp the ring securely and at the same time take a hold of the handles 61 and 71 at the opposite side, thus being able to powerfully exert the needed pressure and twisting motion for the manipulation of the ring or cap.

and enabling the ready removal of the same. When removed the tool serves as a suitable support for the same, while the lamp is being renewed or a repair is being made.

5 By reversing the operation of course the headlight lens can be readily replaced.

It is not essential that the handles 61 and 71 be connected by a hinge 8 although that is the best construction and I show 10 a structure modified by looping a spring 12 into the form of a handle and securing it by rivets 13, 13 to the segments 6 and 7 respectively, as seen in Fig. IV. Other 15 details of the structure can be modified so long as it is provided with effective opposed handles and with proper clamping means for the lens ring or cap.

Having thus described my invention, what I claim as new and desire to secure 20 by Letters Patent, is:

1. A tool for handling headlight lenses comprising a pair of opposed segments, seats L-shaped in cross section formed therein, a suitable cushion within each part, 25 a divided handle one portion of which is secured to one segment and the other to the opposite segment with a hinge therebetween, and a divided and separated projecting handle at the opposite side for 30 grasping and clamping the lens ring or cap, as specified.

2. A tool for handling headlight lenses comprising a pair of opposed segments, 35 seats L-shaped in cross section formed therein, a suitable cushion within each part, a divided handle one portion of which is secured to one segment and the other to the opposite segment, and a divided and separated projecting handle at the opposite side for grasping and clamping the lens ring or cap, as specified.

3. A tool for handling headlight lenses comprising a pair of opposed segments, a divided handle one portion of which is secured to one segment and the other to the opposite segment with a hinge therebetween, and a divided and separated projecting handle at the opposite side for grasping and clamping the lens ring or cap, as specified.

4. A tool for handling headlight lenses comprising a pair of opposed segments, a divided handle one portion of which is secured to one segment and the other to the opposite segment, and a divided and separated projecting handle at the opposite side for grasping and clamping the lens ring or cap, as specified.

In witness whereof, I have hereunto set my hand and seal.

FRANK G. DUNORTH. [L. S.]
